SWITCHING MECHANISM

Albert L. Judson and Carl G. Kronmiller,
Minneapolis, Minn., assignors to Minneapolis-
Honeywell Regulator Company, Minneapolis,
Minn., a corporation of Delaware

Application May 7, 1937, Serial No. 141,300

14 Claims. (Cl. 200—67)

This invention relates to a switching mechanism and more particularly to that type of switching mechanism adapted to open and/or close an electrical circuit or circuits in accordance with changes in the value of a condition such as pressure or temperature.

One object of this invention is the provision of such a switching mechanism having an improved contact structure whereby sticking of the contacts is positively precluded.

Another object is the provision in such a mechanism of a contact structure including means whereby the contacts will always be in proper alignment for engagement with opposed fixed contacts regardless of the position previously assumed by the movable contacts upon disengagement, such as misalignment occasioned by sticking.

A further object resides in the provision in a switching mechanism of a switch box comprising a relatively unitary self contained structure containing the fixed and movable contacts and including a cover so arranged that no circuit may be established through the switching mechanism unless the cover is in its proper position.

A further object is the provision of such a switch box adapted to contain a magnet or magnets to impart a relatively snap action to the movable contact, the magnets being so arranged as to form a substantially integral part of the switch box whereby the fixed contacts, magnets and switch box may be positioned in the switching mechanism as a substantially integral unit.

An additional object resides in the forming and positioning of the magnets in such manner that they will exert a relatively maximum magnetic pull upon the movable contact mechanism and at the same time occupy substantially a minimum of space in the switch box.

A further and more specific object is the provision of a switching mechanism of the type to be hereinafter described which is durable, sturdy, reliable in operation and relatively inexpensive to manufacture.

Other objects will in part be obvious and in part be pointed out hereinafter.

The invention accordingly consists in the arrangements of parts, combination of elements and details of construction, all as will be pointed out more fully hereinafter and disclosed in the accompanying drawing wherein:

Figure 1 is a front elevational view of one form of structure embodying the instant invention.

Figure 2 is a side sectional view taken along

the line 2—2 of Figure 1 as seen from the right.

Figure 3 is a side sectional view taken along the line 3—3 of Figure 4 as viewed from the bottom.

Figure 4 is a sectional view taken along the line 4—4 of Figure 3, certain portions omitted in Figure 3 being disclosed in Figure 4.

Figure 5 is an enlarged sectional view taken along the line 5—5 of Figure 3.

Figure 6 is an enlarged and elevational view 10 of the structure shown in Figure 4, certain portions thereof being broken away.

Figure 7 is a perspective view of a switch box comprising a portion of the instant invention.

Figure 8 is a perspective view of a cover to be utilized in connection with the switch box shown in Figure 7, and

Figure 9 is an enlarged sectional view taken substantially along the line 9—9 of Figure 1 but disclosing the cover in assembled relation 20 with the switch box.

Referring now to the drawing and more particularly to Figure 1 there is generally indicated at 10 a casing to which is secured as by screws 12, a housing 11. Housing 11 is provided with 25 an interiorly disposed peripheral flange 13 to which is secured one end of a bellows 14, the other end of bellows 14 being secured to a plate 15. A depending boss 16 is integrally secured to the base of housing 11 and provided with a passageway 17 extending therethrough. A capillary tube 18 threadedly engages boss 16 and extends to a suitable source of pressure (not shown) which may be positioned in any space, the pressure or other condition of which it is 35 desired to control.

Secured to plate 15 is an operating rod 19 having a pointed tip 20. An annulus 21 positioned about operating rod 19 serves as a seat for one end of a coil spring 22, the other end of which 40 abuts a flange 23, which comprises an integral portion of a stop 24, which latter serves to preclude collapse of bellows 14.

Thus it will be seen that changes in the condition value adjacent the condition responsive 45 bulb are transmitted through tube 18 into casing 11 where such condition value fluctuations serve to expand or contract bellows 14 to move operating rod 19 upwardly or downwardly in a known manner. Spring 22 permits the instrument to 50 operate at subatmospheric pressures, since it is of sufficient strength to bias operating rod 19 to its uppermost position, in the absence of a sufficiently low pressure in housing 11 to occasion downward movement of bellows 14. It will

be understood that if it be desirable that the instrument operate at pressures above atmospheric spring 22 may be omitted.

Point 20 of operating rod 19 abuts a lever 30 pivoted as at 31 to a second lever 32 which includes a pair of abutment members 33 and 34. Lever 32 is in turn pivoted as by a pivot 35 to a bracket 36 secured to a side wall of casing 10. A screw 47 is rotatably secured to the top wall 10 of casing 10 and has positioned thereon a collar 45 having an internally threaded bore 46. Secured to collar 45 is one end of a coil spring 38, the other end of which engages a boss 39 to which is secured a point 40 which in turn abuts lever 30 at a point substantially opposite that at which tip 20 of operating rod 19 engages the same. Thus it will be seen that rotation of screw 45 varies the compression of spring 38, whereby to vary the pressure required in housing 11, to move operating rod 19 and hence lever 30, such variation in pressure corresponding to an increase or decrease in the temperature or other condition in the space adjacent the volatile fluid filled bulb, lever 30 is provided at its distal end with an extending portion 50 parallel to, but out of alignment with, the main body portion.

A resilient member 51 is positioned along and secured to lever 30 whereby disaligned portion 50 and member 51 form a slot into which extends a pin 52. Pin 52 is secured in turn to an insulating block 53 pivoted as by a pivot pin 54 to a bracket 55 carried by the bottom wall of casing 10. An extending portion 56 of bracket 55 is provided with an aperture 57 through which lever 30 is passed and which serves as a stop member to limit movement of lever 30. Thus it will be seen that upon movement of lever 30 in the manner previously described, such movement is transmitted through the pin and slot connection comprised of portion 50, resilient member 51 and pin 52 to insulating block 53 to move the same for a purpose to be described hereinafter. It will further be seen that resilient member 51 serves as a strain release to preclude the transmission of excess movement of lever 30 to insulating block 53 and its associated mechanism.

Means are provided for adjusting the differential of operation of the instrument but form no part of the instant invention being more fully described and claimed in the copending application of Albert L. Judson entitled "Switching mechanism" Serial No. 141,299, filed of even date herewith. These means, therefor, will accordingly be described only in sufficient detail to permit an understanding of the operation of the instrument.

Briefly, the mechanism consists of a lever 62 pivoted on pivot 35 to bracket 36, and a second lever 64 similarly pivoted on pin 35. The extreme ends 66 and 67 of levers 62 and 64 respectively lie adjacent a scale plate 68 secured as by rivets 69 to the top wall of casing 10. Lever 62 is provided with an abutment member 70 through a suitable aperture in which is passed a screw 71. Screw 71 extends exteriorly of casing 10 and is provided with a spring collar 72, serving a purpose to be described hereinafter, and has also an enlarged head 73 having a tool engaging slot 74. Likewise lever 64 is provided with a projection 75, similar to projection 70 and having a corresponding threaded aperture therein through which is passed a screw 76 provided with a spring collar 77 positioned interiorly of casing 10 and biasing the same in a direction in-

wardly from the wall thereof for a purpose to be pointed out hereinafter. Screw 76 likewise has an enlarged head 78, having a tool engaging aperture 79. Thus it will be seen that rotation of screws 71 and 76 respectively vary the position of levers 62 and 64 and their corresponding pointers 67 and 66 for a purpose to be pointed out hereinafter.

Lever 62 is provided, at the end opposite point 67, with a transversely extending portion 80 adapted to abut a flange 81 carried by portion 34 of lever 32. Similarly lever 64 is provided with an abutment 85 positioned for engagement with portion 33 of lever 32. Thus it will be seen that movement of either lever 62 or 64 varies the operating differential of the instrument. Such variation is occasioned by the fact that upon upward movement of operating rod 19 lever 30 moves upwardly therewith about pin 52 rotates lever 32 about pivot 35 until such time as flange 81 abuts transverse portion 80 of lever 62 at which time the rotative movement of lever 30 is continued about pivot 31 in the opposite direction and thence transmitted to insulating block 53 and its associated mechanism. It will also be seen however, that no movement may be transmitted by lever 30 to insulating block 53 until such time as movement of lever 32 has ceased. Conversely upon downward movement of operating rod 20 a similar action will ensue until such time as portion 34 of lever 32 engages abutment 85 of lever 64 whereupon a reverse movement of insulating block 53 will ensue. Thus it will be seen that by varying the position of either abutment 85 or extending member 80 a variable lost motion connection is provided whereby the differential between the condition values at which the instrument operates in opposite directions may be increased or decreased. It will also be seen that the tendency of lever 32, when moved in the manner above set forth, is to urge lever 64 in a direction away from the adjacent side wall of casing 200, and lever 62 in a direction towards the associated side wall.

Thus it will be seen that spring collars 71 and 72 respectively resist this tendency and maintain their associated screw heads in proper position relatively closely adjacent the associated side wall of casing 20.

Having reference now to the particular contact structure which comprises a feature of this invention, an arm 60 extends upwardly from insulating block 53 and is provided at its upper extremity with an aperture 90 closed by a transversely extending member 91 (see Figure 3). Suitable apertures are passed through opposite extremities 91 and accommodate rivets 92 provided with collars 92a at an intermediate point. A contact carrying member 93 provided with contact abutments 94 and 95 is loosely mounted on rivets 92. A pair of leaf springs 96 provided with grooves 97 partially encircling rivets 92 and resting on collars 92a are positioned on opposite sides of contact carrying member 93. A transversely extending bar-like member 98 is positioned outside of the foremost, with respect to member 91, of springs 96 in order to hold the parts in related assembly. Both member 91 and member 98 are provided with rounded bearing surfaces 99. Thus it will be seen that a certain amount of pivotal movement is permitted member 93 and hence contacts 94 and 95 about bearing surfaces 99 which are substantially in alignment with rivets 92. Springs 96, however, serve to hold member 93 and its associated contacts nor-

75 mally in substantial alignment with the vertical axis of arm 60.

Positioned adjacent arm 60 and surrounding contact carrying member 93 is a switch box 100 comprised of insulating material and provided with a relatively large aperture 101 in a wall thereof to permit ingress and relatively free movement of arm 60. Metallic sleeves 102 are embedded in the insulating material comprising switch box 100 (see Figure 9) and provided with transversely extending threaded bores 103 adapted to accommodate threaded contact screws 104 having contact heads 105 and extremities 106 provided with slots to permit engagement of a tool therewith to vary the position of contact heads 105. Contact heads 105 are so positioned as to be engageable by contact buttons 94 and 95 upon opposite sides of switch box 100. Thus it will be seen that springs 96 serve further to maintain a relatively firm contact pressure between contacts 94 and 95 and their associated contact heads 105, since the tendency of springs 76 is to urge contacts 94 and 95 in a direction towards contact heads 95 and to yield resiliently as the contact pressure is increased thereby upon a movement of the contacts towards separation, maintaining a comparatively constant contact pressure until such time as the contacts are separated.

30 It should here be pointed out that contacts 94 and 95 are provided with convex contact surfaces as are also contact heads 105 whereby if sticking occurs between a contact 94 or 95 and either of its associated contact heads 105, a rocking motion of contact carrying member 93 about the axis previously mentioned, in alignment with rivets 92, will pry the contacts apart. Springs 96 serve to restore contacts 94 and 95 to their proper position of alignment for reengagement with their associated contact heads 95 upon release of such sticking.

35 A pair of magnets 110 having relatively beveled inclined edges 110a are positioned in suitable recesses 111 in casing 100 and held in position as by transversely extending bars 112 engaged by screws 113. Magnets 110 serve to impart a relatively rapid or snap action to movement of contact carrying member 93 and its associated contacts through their action on member 91 and bar 98, as member 93 is moved in the manner previously described from the influence of one magnetic field to the other. Magnets 110 are, as better shown in Figure 1, positioned at an angle with respect to contact carrying member 93. Inclined edges 110a, however, are substantially parallel to member 93 and thus exert a relatively great magnetic force thereon, considerably greater than would be exerted were the magnets of conventional shape and so inclined, since, as will be understood, the allocation of the magnetic field upon member 91 or bar 98 increases as the adjacent member approaches the surface of the magnet and due to the fact that surfaces 110a are relatively parallel to the adjacent surfaces of member 91 and bar 98, the closest approach is permitted. The inclination, however, permits the magnets to be disposed in a relatively compact space and at the same time permits a relatively wide clearance at the lower portions thereof, as viewed in Figure 70 1, to permit free movement of arm 60.

75 Metallic sleeves 102 are, as better shown in Figure 9, similarly provided with additional threaded bores 120 at substantially right angles to bores 103. In each of bores 120 is positioned a set screw 121 of a length insufficient to completely fill the

bore which serves to preclude accidental rotation of contact screws 104. The upper extremity of sleeves 102 extend to, and if desirable, slightly above the adjacent surface of insulating material comprising switch box 100. A cover 130 is 5 provided with downwardly extending portions 129 comprising ridges adapted to engage suitable recesses 126 (see Figure 7) formed in switch box 100. Additional recesses 125 are also formed in the side walls of switch box 100 to provide clearance for the heads 106 of contact screws 104 when cover 130 is in position. Cover 130 is provided with a plurality of metallic bushings 132 having apertures 131 therethrough. Bushings 132 are so positioned as to be in substantial registry and physical contact with the upper extremities of bores 120 of sleeves 102. Screws 140 are, as best shown in Figure 9, adapted to pass through apertures 131 and threadedly engage bores 120 above set screws 121. Suitable outside 20 wiring connections 141 may lead from screws 140 to any desired condition control mechanism (see Figure 9).

Thus from the foregoing it will be seen that removal of cover 130 from switch box 100, which 25 may be accomplished only by the release of screws 140, serves to break any possible circuit through the mechanism. It will also be seen that such circuit may not be reestablished until cover 130 is repositioned and properly secured by screws 140 30 to switch box 100. Thus should it become necessary to adjust any of the mechanism contained within switch box 100 it becomes impossible for the adjuster thereof to receive any electrical shock from any circuit through the mechanism. 35 It is further impossible to accidentally close any circuit as by bridging the contacts with a screw driver or other tool. Additionally the use of cover 130 serves to protect the interior mechanism and prevent, to a large extent, the ingress of dirt and 40 foreign matter thereto. However, ready access may be had to the contact structure merely by removing cover 130 in the manner above mentioned.

45 Thus from the foregoing it will be seen that there is herein provided a structure which accomplishes the objects of this invention and others in an improved and advantageous manner and which includes many advantages of great practical importance.

50 Since many embodiments may be made of the above invention and since many modifications may be made in the embodiment above described it is to be understood that all matter herein described or shown in the accompanying drawing 55 is to be interpreted as illustrative and not in a limiting sense.

We claim as our invention:

1. A contact structure for use in a switching mechanism comprising, in combination, an arm, 60 a member, means pivotally securing said member to said arm at an intermediate point, contacts carried by said member adjacent each extremity, leaf springs associated with said means on either side of said member normally biasing 65 the same into substantial alignment with said arm but yieldable to permit pivotal movement thereof upon the application of force to either of said contacts and serving to restore said alignment upon the abatement of said force. 70

2. A contact structure for use in a switching mechanism comprising, in combination, an arm having an aperture therein, a member, means loosely securing an intermediate portion of said member to said arm, a contact disposed adjacent

each extremity of said member, said member being so arranged that one of said contacts is positioned in said aperture, said loosely securing means permitting pivotal movement of said member and hence said contacts with respect to said arm, said one of said contacts moving through said aperture upon such pivotal movement and resilient means normally biasing said member and hence said contacts into substantial alignment with said arm and hence positioning said one of said contacts in said aperture, said resilient means being adapted to yield upon the application of force to either of said contacts but restore said alignment on abatement of said force.

15 3. In a switching mechanism, in combination, a first contact, a second contact movable into and out of engagement with said first contact, means to move said second contact, said means including an arm, means loosely mounting said second contact on said arm, oppositely directed protruding bearing surfaces carried by said arm, and resilient means on each side of said mounting means for normally holding said second contact in alignment with said arm, whereby, upon sticking of said first and second contacts a pivotal movement about said bearing surfaces is imparted to said second contact upon movement of said arm in a direction away from said first contact to cause rotative movement of said second contact with respect to said first contact to release said sticking, said resilient means serving to return said contact to said alignment upon such release.

4. In a switching mechanism, in combination, plurality of fixed contacts, an arm, means to move said arm, a member loosely mounted at an intermediate point on said arm, contacts carried by each extremity of said member adapted to engage said fixed contacts, oppositely directed abutment means carried by said arm, and resilient means on each side of said member normally biasing said member into alignment with said arm but yieldable upon the application of force to said member to permit pivotal movement of said member about said abutment means on said arm, whereby upon sticking of one of said contacts carried by said member, and its associated fixed contact, rotative movement is imparted to said contact carried by said member through said member to release said sticking, said resilient means restoring said member to said alignment upon such release.

5. In a switching mechanism, in combination, a switch box having an aperture therein, a movable arm extending through said aperture, means to move said arm, a contact carried by said arm, a second contact carried by said switch box, a cover for said switch box, a securing member on said cover for engaging said switch box and holding said box and cover in related assembly, leads engaging said securing member and forming part of an electrical circuit which includes said fixed and said movable contacts, and a conductive path between said fixed contact and said securing member whereby said circuit may be closed only when said cover is positioned on said switch box and secured thereto by said securing means.

6. In a switching mechanism, in combination, a switch box having an aperture therein, a movable arm extending through said aperture, means to move said arm, a contact carried by said arm, a second contact carried by said switch box, a cover for said switch box, a securing member on said cover for engaging said switch box and hold-

ing said box and cover in related assembly, leads engaging said securing member and forming part of an electrical circuit which includes said fixed and said movable contacts, and a conductive path between said fixed contact and said securing member whereby said circuit may be closed only when said cover is positioned on said switch box and secured thereto by said securing means, said securing member comprising a screw, and said conductive path a metallic threaded sleeve in electrical association with said fixed contact and positioned for engagement by said screw.

7. In a switching mechanism, in combination, a switch box having an aperture therein, a movable arm extending through said aperture, means to move said arm, a contact carried by said arm, a second contact carried by said switch box, a cover for said switch box, a securing member on said cover for engaging said switch box and holding said box and cover in related assembly, leads engaging said securing member and forming part of an electrical circuit which includes said fixed and said movable contacts, and a conductive path between said fixed contact and said securing member whereby said circuit may be closed only when said cover is positioned on said switch box and secured thereto by said securing means, said securing member comprising a screw, and said conductive path a metallic threaded sleeve in electrical association with said fixed contact and positioned for engagement by said screw and a set screw positioned in said sleeve to secure said fixed contact in a given position, said set screw being relatively short and adapted to be completely encased in said sleeve whereby said first screw may be threaded into said sleeve subsequent to insertion of said set screw therein.

8. In a switching mechanism, in combination, a switch box of insulating material having an aperture therein, a movable arm extending through said aperture, means to move said arm, contacts carried by said arm, sleeves of conductive material embedded in said insulating material, additional contacts positioned for engagement with said first mentioned contacts in electrical engagement with said sleeves, a cover for said switch box also of insulating material, and having apertures therein positioned for registry with said sleeves, metallic members passed through said apertures and engaging in said sleeves comprising part of an electrical circuit including said fixed and said movable contacts, wiring secured to said members in the exterior of said cover, whereby said fixed contacts, said sleeves and said members form a conductive path to said wiring to form an electrical circuit when said fixed and movable contacts are in engagement, and removal of said members and/or said cover means breaks said circuit regardless of the position of said contacts.

9. In a switching mechanism, in combination, a switch box of insulating material having an aperture therein, a movable arm extending through said aperture, means to move said arm, contacts carried by said arm, sleeves of conductive material embedded in said insulating material, additional contacts positioned for engagement with said first mentioned contacts in electrical engagement with said sleeves, magnetic means secured in said casing adjacent said fixed contacts to impart a snap action to the movement of said movable contacts into and out of engagement with said fixed contacts, a cover for said switch box also of insulating material,

and having apertures therein positioned for registry with said sleeves, metallic members passed through said apertures and engaging in said sleeves thereby comprising part of an electrical circuit including said fixed and said movable contacts, wiring secured to said members on the exterior of said cover, whereby said fixed contacts, said sleeves and members form a conductive path to said wiring to form an electrical circuit when said fixed and movable contacts are in engagement, and removal of said members and/or said cover means breaks said circuit regardless of the position of said contacts.

10. In a switching mechanism including fixed and movable contacts and means to move said first mentioned contacts, a fixed contact containing receptacle comprising a casing and a cover therefor of insulating material, contacts embedded in said casing, securing means holding said cover and said casing in related assembly, means forming a conductive path between said contacts and said securing means and leads fixed to said securing means, whereby said leads, securing means and contacts form a conductive path which is broken by disassembly of said casing and cover.

11. In a switching mechanism including fixed and movable contacts and means to move said first mentioned contacts, a fixed contact containing receptacle comprising a casing and a cover therefor of insulating material, contacts embedded in said casing, securing means holding said cover and said casing in related assembly, means forming a conductive path between said contacts and said securing means and leads fixed to said securing means, whereby said leads, securing means and contacts form a conductive path which is broken by disassembly of said casing and cover and a magnet carried by said casing

to impart a snap action to the movement of said movable contacts, whereby said casing, contacts, magnet cover and securing means may be pre-assembled as a substantially unitary relatively compact structure.

12. A contact structure for use in a switching mechanism comprising in combination, an arm having a straight portion and an offset portion, a member loosely carried by said offset portion, a contact mounted on said member, a stationary contact positioned for cooperation therewith, two leaf springs, one on each side of said member normally maintaining it in line with the straight portion of said arm, and means about which said member can fulcrum as said arm moves into or out of contact closing position.

13. A contact structure for use in a switching mechanism comprising in combination, an operating arm, a contact carrying member pivotally secured to said arm, a contact carried by an extremity of said member, and spring means carried by said arm on each side of said member for normally holding said member in substantial alignment with said arm but yieldable to permit pivotal movement of said member when a force is exerted on said contact.

14. In a switching mechanism, in combination, a casing, a stationary contact mounted within said casing, a second contact mounted for movement into and out of engagement with said stationary contact, an opening in said casing providing access to said contacts, a cover for said casing closing said opening and thereby preventing access to said contacts, circuit connections to said contacts, and means for breaking the circuit to said contacts as a direct result of the removal of said cover.

ALBERT L. JUDSON.
